(57) **CLAIM**

The ornamental design for a shell for tobacco products, as shown.

DESCRIPTION

FIG. 1 is a perspective view of the shell for tobacco products of the invention;

FIG. 2 is a front elevation view of the shell for tobacco products of the invention, the rear elevation view being a mirror image thereof;

FIG. 3 is a right side elevation view of the shell for tobacco products of the invention;

FIG. 4 is left side elevation view of the shell for tobacco products of the invention;

FIG. 5 is a top plan view of the shell for tobacco products of the invention, the bottom plan view being a mirror image of the right side elevation view thereof; and,

FIG. 6 is an exploded perspective view for illustrating the component elements of the shell for tobacco products of the invention.
